(57) **CLAIM**

The ornamental design for scissors, as shown and described.

DESCRIPTION

FIG. 1 is a perspective view of the scissors showing my new design;

FIG. 2 is a rear elevational view thereof;

FIG. 3 is a front elevational view thereof;

FIG. 4 is a side elevational view thereof, looking from the left side of FIG. 2;

FIG. 5 is a side elevational view thereof, looking from the right side of FIG. 2;

FIG. 6 is a top plan view thereof;

FIG. 7 is a bottom plan view thereof;

FIG. 8 is an alternate embodiment of the scissors showing my new design;

FIG. 9 is a front elevational view thereof;
FIG. 10 is a rear elevational view thereof;
FIG. 11 is a side elevational view thereof, looking from the right side of FIG. 9;
FIG. 12 is a side elevational view thereof, looking from the left side of FIG. 9;

FIG. 13 is a top plan view thereof; and,
FIG. 14 is a bottom plan view thereof.
